Attorney.

UNITED STATES PATENT OFFICE.

RANDALL W. WALKER, OF OXFORD, NEW YORK.

GUARD-FINGER.

SPECIFICATION forming part of Letters Patent No. 413,116, dated October 15, 1889.

Application filed July 31, 1889. Serial No. 319,313. (No model.)

To all whom it may concern:

Be it known that I, RANDALL W. WALKER, a citizen of the United States, residing at Oxford, in the county of Chenango and State of New York, have invented certain new and useful Improvements in Guard-Fingers; and I do hereby declare that the following is a full, clear, and exact description of the same, reference being had to the annexed drawings, making a part of this specification, and to the letters and figures of reference marked thereon.

This invention relates to certain new and useful improvements in guard-fingers for har-
vesters, and is designed more particularly as an improvement on the device for which I obtained Letters Patent No. 346,568, dated Au-
gust 3, 1886.

It has for its object to provide improved
means for fastening the ledger plate or knife
to the guard.

The invention in the present instance re-
sides in the peculiar combinations and the
novel construction, arrangement, and adapta-
tion of parts, all as more fully hereinafter
described, shown in the drawings, and then
particularly pointed out in the appended
claims.

The invention is clearly illustrated in the
accompanying drawings, which, with the let-
ters of reference marked thereon, form a part
of this specification, and in which—

Figure 1 is a perspective view of my in-
vention. Fig. 2 is a central vertical longi-
tudinal section through the same. Fig. 3 is a
perspective view illustrating the locking de-
vices removed from the guard, but in their
relative positions. Fig. 4 is a perspective
view of the ledger plate or knife removed.

Like letters of reference indicate like parts
throughout the several views.

Referring now to the details of the draw-
ings by letter, A designates a guard-finger,
which may be of any of the usual forms, ex-
cept as hereinafter described. The cross-bar
a of this guard-finger is formed with lugs b
near the ends and with central lug c, leav-
ing upon each side of said central lug a dove-
tail space or channel d, designed to receive
the projections e at the heel of the ledger
plate or knife E. The central lug c of the
cross-bar a is cut away upon its forward face,

as shown at f, and forward of this lug the
guard-finger is formed with a depression g,
which has an opening h extending through
the finger, leaving the shoulders i, for a pur-
pose hereinafter described. The forward wall
of this opening h is formed near the top with
a vertical portion j, below which is the rear-
wardly-inclined portion k, beneath which is
the undercut portion l. The front wall of
the depression g is preferably rounded, as
shown at m.

The ledger plate or knife E is formed at its
forward end with a tapered lug E', designed
to fit a correspondingly-shaped opening in
the guard-finger, as shown in Fig. 2, and at
its rear end, besides the projections e above
described, with a cut-away portion E², and
extending forward from this cut-away por-
tion and centrally thereof is the cut-away
portion E³, the front wall of which is inclined
downwardly and rearwardly, as shown at e'
in Fig. 4. The ledger-plate is sharpened from
the under side, as shown.

The guard-finger is cored or recessed, as
shown at A' in Fig. 2, to lighten the same
and allow slight yielding of the ledger-plate.

B is a locking-plate, formed with a vertical
wedge-shaped shank B', which at its lower
end terminates in a horizontal lug B². At
the upper end of the shank B' is a head B³,
the forward edge of which is shaped to con-
form to the shape of the front wall of the de-
pression g in the guard-finger, the head ex-
tending upon opposite sides of the shank, as
shown in Fig. 3, forming shoulders B⁴, for a
purpose hereinafter described. At the rear
of the head there is a lug B⁵, the forward or
front side of which is undercut, as shown 90
clearly in Figs. 2 and 3.

C is the key, in the form of a wedge, as
shown in Figs. 2 and 3, and is formed with a
T-head C', which has a reduced portion C²,
forming shoulders C³ and shoulders C⁴.

In operation the parts are assembled in the
following manner: The locking-plate B is first
placed in the depression of the guard-finger
with its shank in the vertical hole therein.
The ledger-plate is then placed in position on
the guard-finger, with its lug E' fitting the hole
therefor, with its projections e fitting the
spaces d in the cross-bar a, the shoulders e²
abutting against the shoulders c' of the cen-

tral lug c , but extending inward beyond the same, as shown in Fig. 1. The key C is then dropped into place with its shank in the vertical hole in the finger behind the shank of the locking-plate, as shown. As the key is driven home it forces the locking-plate B forward, its lugs B^2 fitting in the undercut space l of the guard-finger, and its undercut lug B^5 engaging the inclined portion e' of the ledger-plate, as shown in Fig. 2, the **T**-head of the key having its reduced portion C^2 fitting in the recess E^3 of the ledger-plate, the shoulders of the **T**-head serving, as shown in Fig. 1, to prevent displacement of the locking plate or key except by direct vertical movement of the latter. The ledges or shoulders i in the depression of the finger serve as guides and supports for the locking-plate and key, the extended portions of the head of the locking-plate and the shoulders C^4 of the key riding thereon.

The above construction provides a very cheap and efficient means of fastening the ledger-plate, allowing of ready removal or assembling of the parts.

The ledger-plate may be extended more or less upon each side of the guard-finger.

What I claim as new is—

1. The combination, with the guard-finger having vertical aperture, of the ledger-plate, the locking-plate B , and the wedge-shaped key C , substantially as described.

2. The combination, with the guard-finger having vertical aperture and recess l , of the locking-plate having horizontal lug B^2 , fitting said recess, the ledger-plate, and the wedge-shaped key, as set forth.

3. The combination, with the guard-finger having vertical aperture, of the ledger-plate recessed and formed with inclined portion e' , ⁴⁰ the locking-plate having undercut lug B^5 , and the wedge-shaped key, as set forth.

4. The combination, with the guard-finger having vertical aperture, a depression g , and ledges i , of the recessed ledger-plate having inclined portion e' , the wedge-shaped locking-plate having extended head and undercut lug, and the wedge-shaped key, substantially as described.

5. The combination, with the guard-finger ⁵⁰ having vertical aperture, depression g , shoulders i , and recess l , of the recessed ledger-plate having inclined portion e' , the locking-plate having wedge-shaped shank, horizontal lug B^2 , extended head and undercut lug B^5 , ⁵⁵ and the wedge-shaped key having a **T**-head, substantially as shown and described.

6. The combination, with the finger-guard having lugs $b b c$, vertical aperture and spaces d between the lugs, and the lug c , cut away ⁶⁰ upon its front face, of the recessed ledger-plate, the wedge-shaped locking-plate having lug B^5 upon its head, and the wedge-shaped key having **T**-head with reduced portion C^2 , all arranged and operating substantially as ⁶⁵ and for the purpose specified.

In testimony that I claim the above I have hereunto subscribed my name in the presence of two witnesses.

RANDALL W. WALKER.
